UNITED STATES PATENT OFFICE

165,086

SLIP

Philip M. Marcus, New York, N. Y.

Application January 5, 1951, Serial No. 13,683

Term of patent 7 years

(Cl. D3—26)

To all whom it may concern:

Be it known that I, Philip M. Marcus, a citizen of the United States of America, and a resident of New York, in the county and State of New York, have invented a new, original, and ornamental Design for a Slip, of which the following is a specification, reference being had to the accompanying drawing, forming part thereof, in which:

Fig. 1 is a front view of a slip embodying my design showing the shoulder straps broken away.

Fig. 2 is a rear view showing the shoulder straps broken away.

Fig. 3 is an enlarged fragmentary view of the slip shown in Figure 1 illustrating the embroidered trim in detail.

I claim:

The ornamental design for a slip, as shown and described.

PHILIP M. MARCUS.
